AIR CLASSIFIER

Application filed April 2, 1928. Serial No. 266,515.

This invention relates to air classifiers in which removal of the heavier particles from the air is promoted by providing the side walls of a classifier with downwardly inclined corrugations or ribs that serve to direct downward the particles that work out of the path of the air against the side walls of the classifier.

In carrying out the present invention a container is provided having side walls that are positioned to form a narrow air passage between them, and the side walls are provided with corrugations or ribs that slope downwardly in a direction to direct downwardly the particles that work out of the path of the air into contact with the side walls.

It is important that the heavier particles rather than the fine particles work out of the path of the air against the side walls, and this is accomplished in accordance with the present invention by so constructing and arranging the flutes or corrugations of the side walls that they will form a tortuous or serpentine air passage, so that as the materials are carried along this tortuous path by the air the heavier particles will be thrown outwardly against the side wall by the combined action of momentum and centrifugal force, while the lighter particles which are affected to a less degree by these forces will remain in the path of the air.

The heavier particles as a result of the speed with which they are carried through the passage by the air will slide a substantial distance along the downwardly inclined ribs or flutes upon striking a side wall of the container and this will carry the heavier particles rapidly down into the lower portion of the receptacle to effect the desired separation.

If desired various grades of the heavier materials that settle out of the air within the classifier may be secured by providing a series of collecting hoppers along the lower side of the classifier, and air may be introduced at a number of points lengthwise of the air classifier to carry the lighter particles entirely through the classifier.

The various features of the invention and

arrangement of parts will be best understood from the following description when read in connection with the drawings showing one good practical form of the invention.

In the drawings,—

Fig. 1 is a side elevation of the air classifier constructed in accordance with the present invention, parts of the classifier being shown in section;

Fig. 2 is a sectional view taken on the line 2—2 of Fig. 1;

Fig. 3 is a sectional view taken on the line 3—3 of Fig. 1; and

Fig. 4 on an enlarged scale is a horizontal sectional view through a portion of the tortuous air passage.

The air classifier forming the subject matter of the present invention may be variously constructed and may employ a single tortuous air passage as shown, or may be provided with a number of these air passages formed side by side to increase the capacity of the air classifier. Air in most cases will be employed as the carrying medium for conveying the materials to be treated through the air classifier, but it will be understood that water or other fluids may be employed as the carrying medium.

In the embodiment of the invention shown in the drawings the material laden air travels in a horizontal direction through the classifier, but this is not essential in all embodiments of the invention since the air may pass through the air classifier in any desired direction so long as the corrugations or flutes are disposed at an inclination to the path of the air and extend in a direction to carry the materials that travel along the flutes or corrugations out of the path of the air.

In the construction of the invention shown in the drawings the air classifier is provided with the side walls 10 which are spaced from each other to form the narrow air passage 11 between them, and the side walls 10 are fluted or corrugated as shown. The walls 10 at their lower ends are secured to the floor plate 12 and at their upper ends are secured to the cover plate 13.

In the construction shown the left-hand end of the classifier is open to receive air from

the atmosphere and air is exhausted from the opposite end of the classifier by the exhaust fan 14 having the exhaust pipe 15 which leads from the suction side of the fan to the exhaust chamber 16 provided at the right-hand end of the air classifier. It may be desirable to vary the volume of air which enters the inlet end of the classifier and this is accomplished in the construction shown by providing the classifier with the swinging gate 17 which may be moved towards and from the fixed wall 18 to vary the size of the air inlet opening 19. The materials to be treated may be introduced into the air passage 11 near the inlet end thereof by providing the feed hopper 20 having the sliding gate 21 for regulating the flow of the materials from the feed hopper into the air passage, and these materials will be picked up by the air and carried lengthwise of the air classifier in the direction indicated by the arrows.

The side walls 11 of the air classifier are corrugated or fluted as shown and these corrugations or flutes are so arranged that they form a tortuous or serpentine air passage through the air classifier, so that as the air passes along this tortuous air passage the heavier particles will work out of the path of the air against the side walls of the container under the action of momentum and centrifugal force. The centrifugal force will serve to throw the heavier particles out into the loops or channels 22 of the tortuous air passage and the momentum will cause the heavier particles to strike against the side walls instead of following the tortuous path of the air traveling through the classifier.

An important feature of the present invention resides in the construction of the corrugations or flutes of the side walls 10 so that these corrugations or flutes extend diagonally of the path of the air and slope downwardly in a direction to guide downwardly the particles that strike against these flutes or corrugations. Due to the speed with which the materials are carried through the classifier by the air the heavier particles which work out of the path of the air will strike against the flutes or corrugations with considerable force and will slide along these downwardly inclined flutes or corrugations a substantial distance. This will serve to carry these particles downwardly rapidly into the lower portion of the classifier.

It may be desirable to separate the heavier materials that collect in the lower portion of the classifier into various grades and this may be done by providing a series of collecting hoppers 23 along the lower side of the classifier. In the present construction means is provided for admitting air from the atmosphere into the classifier at various points along the same and this is accomplished by providing the collecting hoppers 23 with the

air inlet passage 24, the size of which may be varied as desired by adjusting the sliding gates 25. Within each hopper 23 is preferably mounted a deflector 26 which serves to direct the air downwardly around the deflector plate as shown so that it will pass upwardly through the falling material with a sweeping action that will carry upwardly the finer particles that may tend to settle in the hoppers with the heavier particles. The air exhaust chamber 16 is preferably given the tapered construction shown in Fig. 1 to accommodate the volume of the air which increases in this chamber from the lower to the upper end thereof, and the materials that settle within this chamber will pass downwardly into the collecting hopper 27.

The classifier shown increases in height from its inlet to its discharge end. This is desirable in many constructions to facilitate expansion of the air as it travels lengthwise of the classifier, which in turn will promote settling of the particles out of the air as they approach the discharge end of the classifier.

It will be seen from the foregoing that the downwardly inclined corrugations or flutes formed in the side walls 10 of the classifier perform the double function of working the heavier materials out of the path of the air traveling through the tortuous air passage 11 and of quickly directing these heavier particles downwardly into the lower portion of the classifier by causing them to slide along the downwardly inclined flutes or ribs.

What is claimed is:—

1. An air classifier comprising a container having upstanding side walls disposed in spaced relation to form an air passage between them and provided with corrugations or flutes that extend downwardly diagonally of the path of the air through said passage at an acute angle to the direction of travel of the air stream, and means for advancing material laden air through the passage so that the heavier particles that work out of the path of the air into the channels between the corrugations or flutes will be carried by their velocity along the downwardly inclined channels towards the lower wall of the classifier.

2. An air classifier comprising a container having substantially vertical side walls disposed in close proximity to each other to form a narrow air passage between them, means for advancing material laden air through the narrow passage in a horizontal direction, and the side walls being provided with ribs or flutes that extend downwardly at an acute angle to the direction of the air stream through the passage so that the heavier particles that work laterally out of the path of the air against the ribs or flutes will be carried by their velocity along the downwardly inclined ribs or flutes towards the lower side of the classifier.

3. An air classifier comprising a container

having substantially vertical corrugated side walls arranged to form a narrow serpentine passage between the walls, means for advancing material laden air through the passage, and the corrugations of the side walls being constructed to slope downward at an acute angle to the direction of the air stream through the passage so that the particles that work out of the path of the air against the corrugated side walls will be carried by their velocity along the downwardly inclined corrugations towards the lower side of the classifier.

4. An air classifier comprising a container having approximately vertical side walls spaced to form a narrow air passage between them, means for advancing material laden air through the air passage, the side walls being provided with diagonal ribs or flutes that slope downwardly at an acute angle to the direction of the air stream through the passage so that the particles that work out of the path of the air against the ribs or flutes will be carried by their velocity along the downwardly inclined ribs or flutes towards the lower side of the classifier, and means for introducing additional air into the container at a plurality of points.

5. An air classifier comprising a container having approximately vertical side walls disposed in close proximity to each other to form a narrow air passage between them, means for advancing material laden air through said passage, and the side walls of the passage being provided with downwardly inclined ribs disposed at an acute angle to the direction of the air stream through the passage and adapted to deflect downward the traveling particles that strike these ribs to cause these particles to be carried downwardly along the ribs by their velocity.

In testimony whereof, I have signed my name to this specification.

ALBERT H. STEBBINS.
